STAGE APPLIANCE

Clyde R. Powell, Johnson City, N. Y.

Application December 10, 1936, Serial No. 115,160

12 Claims.

(Cl. 272—8)

My invention relates to a stage appliance and particularly to an apparatus for use by entertainers in producing so-called magic tricks.

In that art of amusement and entertainment wherein tricks are performed with the aid of certain appliances and by the skill of the entertainer to produce mystifying results and illusions, a great many of the tricks so performed depend upon the pulling of a thread at the proper moment for the successful completion and operation of the trick or illusion. Inasmuch as these tricks are generally performed on a stage which is prepared for the occasion by draperies and other effects designed to prevent the observers or audience from seeing the thread, the operation of such tricks calling for the use of a thread has been fairly satisfactory. Particularly is this true where the entertainer has an assistant on the stage with him and who, unobserved by the audience, can pull the thread at the proper moment.

In cases, however, where the stage setting cannot be prepared fully, or where no stage is provided for the entertainer, such as at impromptu gatherings and parties, and where it is difficult to conceal the thread, and also in cases where the entertainer is without assistance on the stage and must perform all the operations of his tricks himself, it is difficult to manipulate the thread pulling without detection.

The principal object of my invention is to provide a robot or apparatus for automatically pulling the thread without any action or effort on the part of the entertainer beyond providing sound vibrations by means of which the thread pulling device is released.

It is also an object of my invention to provide a thread pulling means releasable by sound vibrations in combination with novel effects and illusions operable thereby and conjointly therewith.

A still further object of my invention lies in the provision of an appliance for creating the illusion of an article being shot from a gun on to a target, the operation of the device being dependent upon the sound vibrations resulting from the firing of the gun.

Another object of my invention lies in the provision of a novel means for setting the apparatus for operation.

Other objects and advantages will be apparent as the description proceeds, reference now being had to the figures of the accompanying drawings forming a part of this application, and

wherein like reference numerals indicate like parts.

In the drawings:

Figure 1 is a perspective view of an apparatus embodying my invention.

Figure 2 is a detail rear view of a portion of the illusion producing device.

Figure 3 is a detail rear view of such device illustrating an independent sound operated releasing means therefor.

Figure 4 is a top plan view of one form of my robot thread pulling device, shown in cooperation with one type of trick or illusion device to which it is applicable.

Figure 5 is a top plan view of a modified form of my robot thread pulling device.

Figure 6 is a detail sectional view of the releasing means of the robot shown in Figure 5.

Figure 7 is a detail sectional view of the setting device for my robot, illustrating in full and in dotted lines two positions thereof.

Figure 8 is a detail sectional view similar to Figure 7, illustrating a third position of the setting means.

The reference character 1 refers to a shallow box or housing within which the mechanism comprising my robot thread pulling device is disposed. This casing 1 is provided with a removable cover 2 having a longitudinal and centrally disposed slot or opening 3 therein. Fastened to the cover 2 is an inverted substantially U-shaped supporting bracket 4 over the top of which may be looped ribbons or supporting bands 5 adapted to support a small pane of glass 6 or the like. The purpose of these elements will be apparent as the description proceeds.

Disposed within the casing 1 and beneath the cover 2, (see Figure 4), is pivotally mounted, as at 7, an armature bar 8 extending substantially across the casing 1 adjacent one end thereof. This armature bar is disposed intermediate its length between the legs of an inverted U-shaped bracket 9 suitably secured to the bottom of the casing and which serves to limit the pivotal movement of the armature bar. A coil spring 10 has one end secured to the adjacent end of the casing and the opposite end to the free end of the armature bar to normally urge the same in a direction toward the adjacent end of the casing.

Suitably mounted on the bottom of the casing 1 adjacent the free end of the armature bar 8 is an electromagnet 11, the current for which is supplied from a suitable source such as the dry cell batteries 12 secured in holders 13 in the casing. When the circuit between the batteries 12

and the magnet 11 is closed the magnet is energized, and, if the armature arm 8 is moved into engagement with the magnet during such energization, against the tension of the spring 10, 5 the magnetic energy of the magnet is sufficient to retain the armature bar in such position (as shown in Figure 4) against the tension of the spring 10 and the armature will remain in such position until the circuit is broken whereupon the 10 spring 10 will instantly pull the armature bar 8 away from the magnet. The armature bar 8 is provided substantially centrally with an opening 14 adapted to receive the free end of a rod 15 mounted upon a pivoted bracket 16 pivoted on a 15 pintle 17 around which is disposed a heavy coil spring 18 adapted to urge, with great force, the rod 15 to the dotted line position shown in Figure 4, that is, away from the armature bar 8. A strip of padding material 19 is provided on the 20 bottom of the casing 1 against which the rod 15 may strike as it is forcibly thrown into engagement therewith under the action of the heavy coil spring 18. With the rod 15 pivoted to the position shown in full lines in Figure 4, to bring 25 its free end into alignment with the opening 14 in the armature bar 8, and with such armature bar moved into engagement with and held in such position by the magnet 11, the armature bar serves as a latch device for the rod 15. Upon 30 breaking the circuit to the magnet 11, the armature bar is pulled away by the spring 10, thus releasing the rod 15 to fly back to its normal position against the pad 19. The opening 3 in the cover 2 is aligned with this rod 15 and permits 35 such movement.

The means for making and breaking the electric circuit to the magnet 11 is the same as is used in the various forms and modifications of the invention shown herein and is illustrated in 40 detail in Figures 3 and 6. This means comprises essentially a light pivoted contact member 20, pivoted as at 21 to one end of the casing 1 and having its free end lightly engageable against a diaphragm element 22 suitably secured across an 45 opening 23 formed in the end of the casing. Both the fixed diaphragm element 22 and the pivoted contact member 20 are included in the circuit between the batteries 12 and the magnet 11. Normally the contact member 20 rests lightly against 50 the diaphragm 22 to complete the circuit. This pivoted contact member 20 is so light, however, that it is sensitive and responsive to sound vibrations such as, for instance, those caused by the detonation of a blank cartridge in a gun or the 55 like, causing the contact member 20 to vibrate and with such vibration to disengage the diaphragm contact member 22 for an instant thereby breaking the circuit between the batteries 12 and the magnet 11, and permitting the spring 10 to pull 60 the armature bar 8 away from the magnet to release the bar 15 as previously explained. The opening 23 through the casing wall facilitates the sound waves reaching the contact member 20.

The armature bar 8 is also included in the 65 circuit of the magnet and batteries so that as long as the armature bar is out of engagement with the magnet, even though the contact maker and breaker elements 20-22 are engaged, no current will be drawn from the batteries 12. This is 70 shown clearly in Figure 4.

Attached to the free end of the rod 15 is a 75 thread 24 which may be disposed in any suitable manner to pass through and out of the casing 1 either through an opening in the wall thereof or between the wall and the cover 2, and which may

be guided and led in any desired direction and for any desired distance to the apparatus or trick illusion device which it is desired to operate by the pulling of the thread 24. Such devices are many and varied in number and character and as 5 illustrative only I have shown in Figure 4 one form of such device in order to illustrate the operation of my robot thread pulling device.

The opposite end of the thread 24 is secured as at 25 to a wire releasing member 26 substantially U-shaped and having the legs 27 adapted, in the illustration shown, to pass through suitable openings in the cover 28 of a glass jar 29 disposed in full view of the audience. Overlying the release member 26 in the cover 28 may be any desired articles such as a great number of folded colored papers or spring flowers, flags, handkerchiefs, or other articles compressed to the desired small space within the cover 28 and which, when the releasing member 26 is pulled out of holding 20 position, are released to drop into the glass jar 29 in sight of the audience. Thus with the apparatus set as shown in Figure 4, upon the shooting 25 of a blank cartridge in a gun, or otherwise providing a detonation or sound waves, the contact member 20 vibrates and breaks the circuit to the magnet 11 whereupon the spring 10 pulls the armature bar 8 away from the magnet, releasing the rod 15, which under the influence of the heavy coil spring 18, flies over and against the pad 19, 30 this movement being so fast as not to be visible to the audience looking at the device. During such rapid movement of the rod 15, the thread 24 is pulled, thus pulling the latch device 23 from the cover 28 of the jar 29 and releasing the 35 articles trapped therein for movement into the jar 29 to produce the illusion of the operator having shot the articles into the glass jar with the gun.

With reference to Figure 1 of the drawings, it 40 will be observed that if the pane of glass 6 is suspended on the ribbons 5 in the path of the rod 15, as it flies over from the latching position to the pad 19, the glass pane will be broken by the rod during such movement. If the glass is not provided in this position, the rod simply flies over freely.

The use of this device with the glass pane 6 is usually in combination with another illusion or trick effect device in the form of a target which 50 the entertainer shoots at with the gun "through" the glass 6. This target device comprises a casing 30, the front wall 31 of which is marked off as at 32 after the appearance of a target, the concentric circles of the target being clearly visible 55 to the audience. This casing is disposed in alignment with the glass pane 6 and with the end of the casing 1 in the ordinary performance of this trick.

The center circle 33 of the target is a separate 60 piece from the front wall 31 but is skillfully fitted and so painted with respect to the outer concentric circles of the target that the fact that it is a separate panel is not detectable by the audience. This center panel 33 is provided on the rear surface of the front wall 31 with vertically disposed pintles 34 by means of which the panel is pivoted for rotation about a vertical axis. Surrounding the pintles 34 are heavy coil springs 35 tending to normally urge the panel 33 in one direction. 70 The panel 33 is provided at one point on its edge with a projection 36 adapted to be engaged by a pivoted latch 37 normally urged in a direction to engage the projection 36 whereby to hold the panel 33 in one position against the tension of 75

the springs 35, by means of the coil spring 38. Obviously when this latch 37 is moved to releasing position, the panel 33 under the influence of the heavy springs 35 will rotate instantly and at 5 a speed faster than the eyes of the audience can detect, to reverse the sides of the panel and present the rear side thereof to the front as the inner concentric circle of the target. In this movement the projection 36 engages against the 10 rear side of the front wall 31 and serves as a stop to prevent further movement of the panel.

Both sides of the panel 33 are provided with a hook 39, the hook on the rear side being adapted to receive a watch 40 or other article which may 15 be used in adding to the amusement and entertainment of the illusion.

As an illustration of the operation of this invention, the latch 37 may have secured thereto one end of the thread 24 connected at its opposite 20 end to the free end of the rod 15.

In the operation of this trick, the entertainer may lead up to the operation of the illusion in many ways such as for instance by borrowing a watch from someone in the audience. Once he 25 has the watch in his hand, he immediately palms it and substitutes for it a cheap imitation watch which he then breaks up into pieces and packs into the end of a gun. Previously he has attached to the hook 39 on the rear side of the panel 33 another watch. He then aims the gun at the 30 target through the pane of glass 6 and fires a blank cartridge in the gun. The detonation of the cartridge operates the contact maker and breaker 20 to break the circuit to the magnet 11 as before explained, whereupon the rod 15 flies over to its normal position breaking the glass 6 as it does so and simultaneously pulling the thread 24 which operates the latch 37 to release the panel 33 which simultaneously reverses its 35 position—too quickly for the eye to see—and there appears as if by magic the watch hanging on the hook 39. This effect is particularly natural inasmuch as the rapid swinging movement of the panel 33 causes the watch 40 which is hanging on the back of the panel to swing outwardly during such movement so that as it appears on the front of the target, it is swinging back to its normal position against the panel, giving the illusion of having been shot there and is just settling into place on the hook 39. To complete the 40 trick, the entertainer thereupon removes the watch from the hook, immediately palms it, and returns the owner's own watch to him.

This target trick may also be operated entirely 45 independently of the thread pulling mechanism and as an independent illusion in itself by providing a release for the panel 33 operable by the detonation of the gun directly. This form is shown in Figure 3 and wherein an armature bar 41 is pivoted intermediate its ends as at 42, one end being engageable with the projection 36 on the panel 33 and the opposite end being engageable with a magnet 43, the current for which is supplied by batteries 44 and in the circuit of 50 which is the same sound vibration operated contact maker and breaker 20 previously described.

Obviously in the operation of the target trick independently of the thread pulling device, the firing of the gun serves to break the circuit to 55 the magnet 43 by vibrating the contact member 20 and permitting the coil spring 45 to move the armature bar 41 out of latching engagement with the projection 36 whereupon the panel 33 is permitted to reverse its position as before explained.

75 In Figures 5 and 6 I have shown a modified

form of the robot thread pulling device and wherein there is provided adjacent the armature bar 8 a bracket 46 upon which is pivotally mounted a latch 47 provided with two hook portions 48 and 49. A fixed pin 50 on the bracket 46 limits 5 the pivotal movement of the latch 47 in both directions.

The hook portion 49 of the latch is adapted to engage in the opening 14 of the armature bar 8, when such bar is in engagement with or directly 10 adjacent to the magnet 11. The other hook portion 48 of the latch 47 is adapted to loosely receive a small eyelet or ring 51 secured to the free end of an elastic 52 such as a rubber band or coil spring or any other elastic device which is adapted 15 to resume its contracted position after expansion. The opposite end of the elastic 52 is suitably secured to the opposite end wall of the casing 1. When the elastic 52 is secured to the latch 47 as shown in full lines in Figure 6, such elastic is 20 stretched and under tension. The ring or eyelet 51 also has secured thereto one end of a thread 53, the opposite end of which may be attached to any desired device which it is desired to pull in in order to produce a trick or illusion, such as 25 the latch 37 of the target device or the latch 26 of the transparent jar trick or to lift a card from a deck or any of many other tricks known in the art.

With the armature bar 8 in engagement with 30 the magnet 11 and held in such position by the energy of the magnet, and with the elastic 52 secured to the latch 47 by means of the ring 51 engaging the hook 48, and with the hook portion 49 engaged in the opening 14 in the armature bar 35 8, the latch 47 is prevented from rotating to release the elastic 52. Obviously however, upon breaking the circuit of the magnet 11 and thus releasing the armature bar 8 to move away from the same under the influence of the coil spring 40 10, the latch member 47 rotates about its pivot to the dotted line position of Figure 6, whereupon the link 51 and elastic 52 are released and instantly contract to the normal position shown in dotted lines in Figure 6, resulting in giving an 45 instantaneous pull on the thread 53.

It will be understood that an entertainer in preparing for a program of tricks and illusions, prepares his apparatus in advance of the performance and in the use of the thread pulling 50 robot herein described, of either the form shown in Figure 4 or that shown in Figure 5, it is, of course, desirable that the rod 15 be previously engaged in latched engagement with the armature bar 8 or the latch 47 engaged in latched 55 position with the armature bar 8 so as to avoid hooking these members together during the performance. At the same time it is undesirable to leave the armature bar 8 in engagement with the magnet 11 during any appreciable length of time 60 leading up to the use of this particular apparatus in the performance.

I have therefore devised a setting device by means of which the latches can be previously disposed in latching position and will remain in such position until the apparatus is ready to use, without engaging the armature bar 8 with the magnet until it is time to use the device, whereupon the armature bar can be quickly and inconspicuously engaged with the magnet and the setting device 65 positioned to permit the free and instant release of the armature bar and latches upon the performance of the trick.

This setting means is shown in Figures 4, 5, 7 and 8, and comprises a rotatable pin 54 extending 75

through the side of the casing 1 and provided on its outer side with a fingerpiece 55 whereby it may be readily turned. This fingerpiece is small and inconspicuous and may be readily concealed from the sight of the audience.

5 The inner end of the pin 54 carries a cam disk 56 eccentrically mounted as at 57 on the inner end of the pin 54. The disk 56 is provided with a flat edge portion 58.

10 The normal position of this setting device is shown in full lines in Figure 7 with the eccentric disk 56 turned to permit the spring 10 to pull the armature bar 8 the full limit of its distance away from the magnet 11, as determined by the 15 stop bracket 9. In this position the end of the rod 15 will not engage in the opening 14 of the armature bar nor will the hook portion 49 of the latch member 47 engage in such opening.

If, however, the disk 56 is rotated to the position 20 shown in dotted lines in Figure 7, it will be noted that it moves the armature bar 8 into engagement with the magnet 11. At this point the disk can be returned to the full line position of Figure 7 in which position the release of the 25 armature bar will cause the release of the rod 15 or the latch 47, or the disk 56 may be turned further in the same direction to bring the flat edge 58 thereof flat against the side of the armature bar 8, as shown clearly in Figure 8. In this position 30 the circuit may be broken by either moving the armature bar 8 away from the magnet manually or by jarring the contact member 29 to break the circuit and permit the spring 10 to pull the armature bar back against the flat side of 35 the disk 56. The disposition of the disk is such that in this position, shown in Figure 8, the movement of the armature bar against the flat side of the disk is not sufficient to release the rod 15 nor the latch 47 from the bar. This is the safety 40 position and in which position the apparatus may be left for any length of time until ready to use with the latches engaged but without drawing current from the battery 12. When the operator is ready to use the robot to pull a thread or operate a trick illusion, he simply turns the disk 56 45 back to the position shown in full lines in Figure 7 from the position shown in Figure 8, during which movement the disk forces the armature bar into engagement with the magnet, re-establishing 50 the current which will hold the bar in such engagement, and moves the disk far enough away from the armature bar to permit the unlatching of the rod 15 and the latch 47 upon breaking the circuit through means of the contact member 29 55 as previously described.

It is believed that from the foregoing description and explanation, the operation of my invention will be clear. It will be understood, of course, that many changes may be made in details of construction and arrangement of parts without departing from the spirit and scope of my invention. I do not limit myself therefore, to the exact form herein shown and described other than by the appended claims.

65 I claim:

1. In combination with a stage illusion device operable by pulling a thread, a member adapted to be placed under tension, a thread connecting said member and said device, means for latching said member in tensioned position, and means operable by sound vibrations for releasing said latching means whereby said tensioned means resumes its normal position and in so doing pulls said thread.

70 2. A thread pulling device for stage illusions

and the like comprising a member movable from normal position to a position under tension, latch means for holding said member in tensioned position, means responsive to sound vibrations for releasing said latch to permit said member to return to normal position, and a thread secured to 5 said member.

3. A thread pulling device for stage illusions and the like comprising a member movable from normal position to a position under tension, latch 10 means for holding said member in tensioned position, said latch means including an electromagnet, means responsive to sound vibrations for breaking the circuit to said magnet and releasing said latch means to permit said member to 15 return to normal position, and a thread secured to said member.

4. A thread pulling device for stage illusions and the like comprising a member movable from normal position to a position under tension, 20 latch means for holding said member in tensioned position, said latch means including an electromagnet, means responsive to sound vibrations for breaking the circuit to said magnet and releasing said latch means to permit said member to 25 return to normal position, and a thread secured to said member, said sound responsive means including a light vibratile contact member in the electric circuit of said electromagnet.

5. A thread pulling device for stage illusions 30 and the like comprising a casing, a pivoted member in said casing adapted to be moved from normal position to a position under tension, a latch for holding said member in tensioned position, a cover for said casing, said cover having a slot 35 therein through which said member swings to and from its normal and tensioned positions, means responsive to sound vibrations for releasing said latch, and a thread secured to said member.

40 6. A thread pulling device for stage illusions and the like comprising a casing, a pivoted member in said casing adapted to be moved from normal position to a position under tension, a latch for holding said member in tensioned position, 45 a cover for said casing, said cover having a slot therein through which said member swings to and from its normal and tensioned positions, means responsive to sound vibrations for releasing said latch, a thread secured to said member, and breakable means on said cover in alignment with said slot whereby said member will strike and break the same in its movement from tensioned position to normal position.

7. A stage illusion device comprising a target 55 having a pivoted center panel reversible with respect to the front surface of said target, a supporting hook on each face of said panel, tension means for normally urging said panel to a position with one face coincident with the front surface of said target, means for latching said panel under tension with its opposite face coincident 60 with the front surface of said target, and means controlled by sound waves for releasing said latching means whereby said panel reverses its 65 position.

8. A stage illusion device comprising a target having a pivoted center panel reversible with respect to the front surface of said target, a supporting hook on each face of said panel, tension 70 means for normally urging said panel to a position with one face coincident with the front surface of said target, means for latching said panel under tension with its opposite face coincident with the front surface of said target, and means 75

controlled by sound waves for releasing said latching means whereby said panel reverses its position, said latching means and releasing means being mounted upon the rear surface of 5 said target.

9. A thread pulling device for stage illusions and the like comprising a member movable from normal position to a position under tension, latch means for holding said member in tensioned position, said latch means comprising an electromagnet and a pivoted armature adjacent thereto, said armature being adapted when in engagement with said magnet to complete the circuit to said magnet and be held thereby, said armature also being engageable by said member to latch the latter when engaging said magnet, and means responsive to sound vibrations for breaking the circuit to said magnet to permit said armature to move away from said magnet and 10 release said member.

10. A thread pulling device for stage illusions and the like comprising a member movable from normal position to a position under tension, latch means for holding said member in tensioned position, said latch means comprising an electromagnet and a pivoted armature adjacent thereto, said armature being adapted when in engagement with said magnet to complete the circuit to said magnet and be held thereby, said armature also being engageable by said member to latch the latter when engaging said magnet, and means responsive to sound vibrations for breaking the circuit to said magnet to permit said armature to move away from said magnet and 15 release said member.

11. A thread pulling device for stage illusions and the like comprising a member movable from normal position to a position under tension, latch means for holding said member in tensioned

position, said latch means comprising an electromagnet and a pivoted armature adjacent thereto, said armature being adapted when in engagement with said magnet to complete the circuit to said magnet and be held thereby, said armature 5 also being engageable by said member to latch the latter when engaging said magnet, means responsive to sound vibrations for breaking the circuit to said magnet to permit said armature to move away from said magnet and release said member, a spring normally urging said armature away from said magnet, and a setting means for said device comprising a rotatable cam engageable with said armature to move the same into engagement with said magnet. 10

12. A thread pulling device for stage illusions and the like comprising a member movable from normal position to a position under tension, latch means for holding said member in tensioned position, said latch means comprising an electromagnet and a pivoted armature adjacent thereto, said armature being adapted when in engagement with said magnet to complete the circuit to said magnet and be held thereby, said armature also being engageable by said member 20 to latch the latter when engaging said magnet, means responsive to sound vibrations for breaking the circuit to said magnet to permit said armature to move away from said magnet and release said member, a spring normally urging 25 said armature away from said magnet, a setting means for said device comprising a rotatable cam engageable with said armature to move the same into engagement with said magnet, and said cam having means operable in one position thereof to permit disengagement of said armature from said magnet a limited amount but retaining it in a position to prevent unlatching said member. 30 35

CLYDE R. POWELL. 40
